Primary Examiner — Mitchell I. Siegel(74) *Attorney, Agent, or Firm* — Kirton McConkie; Evan R. Witt(57) **CLAIM**

The ornamental design for a toy scoop paddle, as shown and described.

DESCRIPTION

FIG. 1 is a bottom, front and left side perspective view of a toy scoop paddle, showing my new design;

FIG. 2 is a bottom, rear and left side perspective view thereof;

FIG. 3 is a top, front and left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken line portions in the drawing views are included to show unclaimed subject matter only and form no part of the claimed design.
